UNITED STATES PATENT OFFICE

THOMAS J. HOWE AND HENRY N. LABARE, OF OWATONNA, MINNESOTA;
ASSIGNORS TO THE OWATONNA MANUFACTURING COMPANY, OF SAME
PLACE.

DETACHABLE GRAIN-DRILL SHOE.

SPECIFICATION forming part of Letters Patent No. 643,410, dated February 13, 1900.

Application filed September 8, 1899. Serial No. 729,802. (No model.)

To all whom it may concern:

Be it known that we, THOMAS J. HOWE and HENRY N. LABARE, of Owatonna, Steele county, Minnesota, have invented certain new and useful Improvements in Detachable Grain-Drill Shoes, of which the following is a specification.

This invention relates to the shoes of grain-drills; and the object of this invention is to provide means whereby the drill-shoe may be readily separated from the shank and drag-bar, so as to permit the shoe to be sharpened or to permit a new shoe to be substituted therefor, if necessary.

15 The invention consists generally in improved means for attaching and locking the removable shoe to the shank and drag-bar.

The invention consists, further, in the constructions and combinations hereinafter described, and particularly pointed out in the claims.

In the accompanying drawings, forming part of this specification, Figure 1 is a side elevation of a grain-drill shoe embodying our invention. Fig. 2 is a plan view. Fig. 3 is a longitudinal section showing the interior of the hollow shank and showing in detail the mechanism for securing the shoe to said shank.

In the drawings, 2 represents a hollow shank 30 or tube of ordinary form and construction, through which the grain is dropped by the mechanism of the drill. At its lower end the shank 2 is provided with a forwardly-extending projection 3, to the upper part of which the end of the drag-bar is secured by a bolt, rivet, or other suitable means. The drag-bar 4 consists, preferably, of two members arranged with a space between them and preferably curved near the shoe-shank to fit 35 the curved upper edge of the shoe 5. The shoe is hollow and of the usual form and receives the projection on the lower end of the shank. The shoe is open at its rear end, so that the grain passing through the hollow 40 shank or tube passes out of the rear end of the shoe and into the drill formed by the shoe. The two members of the drag-bar diverge at a point preferably a short distance forward of the forward end of the shoe, as shown in 45 Fig. 2 of the drawings. Within the hollow shoe we provide a suitable block or lug 6,

preferably held in position by a pin 7 or other suitable means. One end of the block may be of rounded form, as shown in the drawings, to fit within a socket or recess of corresponding form in the forward edge of the projection 3. The rear portion of the shoe is thus supported by said projection and is firmly held in position. Between the two members of the drag-bar and at a point just 60 in front of the shoe when in position we provide a cam-lever 9, adapted to engage the inclined forward end 10 of the shoe, which is arranged to pass between the two parts of the drag-bar.

65 The shoe is secured in position by causing the block 6 to enter the recess in the forward part of the projection 3 and raising the forward end of the shoe between the two parts of the drag-bar, the cam-lever being in the 70 position indicated by dotted lines in Fig. 3 during this operation. The lever is then turned to the position shown by full lines in Figs. 1 and 3, and the cam-surface engaging the forward end of the shoe shoves the shoe 75 backward until the block 6 is firmly seated in the recess in the projection 3. The same movement of the cam-lever also raises the forward end of the shoe and brings each side plate thereof into close contact with the under side of the corresponding member of the drag-bar. This is accomplished by the cam-surface of the lever coming in contact with the inclined forward end of the shoe. This 80 inclined forward end of the shoe is in the 85 form of a lug that projects between the two members of the drag-bar and is therefore of substantially the thickness of the space between said members, while the top of the shoe itself is substantially of the thickness of 90 the drag-bar and when in position fits closely against the under surface thereof, one side of the shoe fitting against one member of the drag-bar and the other side against the other. The cam-lever is also preferably provided 95 with the projections 13, which prevent the end of the lever from passing at any time downward through the space between the parallel portions of the members of the drag-bar. When the lever is released, however, it is 100 thrown over to the position indicated in dotted lines in Fig. 3, and these projections pass be-

tween the members of the drag-bar forward of the pin upon which the lever is pivoted, the space between the two members of the drag-bar at this point being sufficient for this purpose. It is not intended that the end of the cam-lever shall strike the top of the drag-bar when the shoe is locked in position, but the parts are intended to stand in the position shown in Fig. 3 of the drawings. Should there, however, be wear of the parts the end of the lever might come down to the top of the drag-bar, and then these projections would come in contact with the drag-bar and prevent any further movement of the lever. When the lever is thrown forward into the position shown by dotted lines in Fig. 3 for the purpose of releasing the shoe, a space is left between the forward end of the shoe and the lever, and the shoe may then be moved forward until its rear end is disengaged from the shoe-shank, and the shoe may then be readily detached.

The shoe, it will be seen, is readily detachable. There are no loose or removable parts. 25 The lever forms a permanent part of the drag-bar, and the other devices are permanently attached either to the shoe or to the shank.

We do not confine ourselves to the details of the construction herein shown and described, 30 as the same may obviously be varied in many particulars without departing from our invention.

Having thus described our invention, we claim as new and desire to secure by Letters 35 Patent—

1. The combination, with the grain-drill shoe-shank and the drag-bar secured thereto, of the removable shoe, means for securing the rear end of the shoe to the shoe-shank, and a 40 cam-lever engaging the forward portion of said shoe and locking the same to said drag-bar.

2. The combination, with a grain-drill shoe-

shank and a drag-bar connected thereto, of a detachable shoe, means for securing the rear end of said shoe to said shank, a cam-lever 45 pivotally supported upon said drag-bar and adapted to engage and lock the forward end of said shoe, for the purpose specified.

3. The combination, with a grain-drill shoe-shank, and a drag-bar secured thereto and 50 consisting of two members, suitably separated, of a detachable shoe, means for securing the rear end of said shoe to said shank, a cam-lever pivotally supported between the two members of the drag-bar and adapted to engage 55 the inclined forward end of said shoe, for the purpose set forth.

4. The combination, with the shoe-shank and drag-bar, of the detachable shoe, means for securing the rear end of said shoe to said 60 shank, said shoe being provided with an inclined forward end adapted to pass into the space between the parts of the drag-bar, and a cam-lever arranged to engage the inclined forward end of said shoe, for the purpose set 65 forth.

5. A grain-drill shoe, having means thereon for engaging a shoe-shank and having an inclined forward end adapted to be engaged by a cam-lever, for the purpose set forth. 70

6. A detachable grain-shoe having means thereon for engaging a shoe-shank by a rearward movement, and having its forward end adapted to be engaged by a cam-lever, for the purpose set forth. 75

In testimony whereof we have hereunto set our hands, this 4th day of September, 1899, at Minneapolis, Minnesota.

THOMAS J. HOWE.
HENRY N. LABARE.

In presence of—
A. C. PAUL,
RICHARD PAUL.
